UNITED STATES PATENT OFFICE.

EDWIN H. BELL, OF CHICAGO, ILLINOIS.

PROCESS FOR MANUFACTURING TIE-PLATES.

1,089,389.

Specification of Letters Patent. Patented Mar. 10, 1914.

Application filed August 18, 1911. Serial No. 644,866.

To all whom it may concern:

Be it known that I, EDWIN H. BELL, a citizen of the United States, and a resident of Chicago, in the county of Cook and State 5 of Illinois, have invented certain new and useful Improvements in Processes for Manufacturing Tie-Plates; and I do hereby declare that the following is a full, clear, and exact description thereof, reference being 10 had to the accompanying drawings, and to the letters of reference marked thereon, which form a part of this specification.

This invention relates to an improvement in the process of manufacturing railway tie- 15 plates of the kind made of rolled metal and in which the tie-plate is provided on its upper surface at one end with an elevated part or rib forming a rail-abutting shoulder and at its opposite end with elevated spike- 20 head seats having upwardly facing bearing surfaces or seats for contact with the annular downwardly facing shoulders on the heads of screw spikes extending through the tie-plate. The said rib at either side of the 25 rail-abutting shoulder is so formed on its upper surface as to provide upwardly facing seats for the heads of the screw spikes extending through the tie-plate adjacent said shoulder.

30 The invention consists of the matters hereinafter described and more particularly pointed out in the appended claim.

In order to illustrate my improved process, I attach hereto drawings, in which— 35 Figure 1 is a perspective view illustrating a series of tie-plate blanks, as they appear when the continuous plate from which they have been rolled, has been severed along transverse lines separating the tie-plate 40 blanks; Fig. 2 is a top plan view of the continuous plate after it has been rolled to form tie-plate blanks and before the same has been severed to separate the said blanks; Fig. 3 is a view representing a section 45 through a pair of rolls adapted for rolling my improved tie-plates in accordance with my improved process; Fig. 4 is a view representing a front elevation of the coating surfaces of the said rolls; Fig. 5 is a view representing a fragmentary section through 50 Fig. 3 in a plane indicated by the line 5—5 thereof.

Referring now to the drawing, 10 indicates the continuous plate from which the 55 tie-plates are rolled and which is of uniform

cross-section before it passes between the rolls 11 and 12 and which is formed by said rolls into a continuous plate 13 consisting of a plurality of successive tie-plate blanks 13^a arranged end to end (see Figs. 2 and 3). 60 The continuous plate 13 is then severed along dotted lines 13^b, 13^b, to separate the said tie-plate blanks from each other.

14 indicates an elevated part or rib formed at one end of each tie-plate blank and having a flat upright face 14^a extending transversely of the plate and constituting a rail-abutting shoulder. The tie-plate is designed to have round spike holes through the ends of the rib 14, and said rib exterior to the location 65 of said spike holes is formed to provide elevated spike-head seats 15, 15, having upwardly facing bearing surfaces or seats for contact with the annular downwardly facing shoulders on the heads of the screw 70 spikes which also engage and bear upon the inclined top surface of the base-flange of the rail, and the spike-head seats 15, 15 are inclined to correspond with the inclination of the shoulders of the spike-heads, so that the 75 latter will have firm bearing both on the rail flange and upon the spike-head seats. The part of the rib 14 between the elevated seats 15, 15, is shown as formed by means of a plurality of rounded projections 14^b, 14^b, 80 joined with each other, and with the said seats so as to form in effect a continuous rib, although they need not necessarily be so formed. Such construction is preferred, however, in order to facilitate the formation 85 of the rib in the process of rolling the plate, as set forth in my prior Patent No. 879,238, dated February 18th, 1908. As shown in the drawings, the upright face 14^a of the rib 14 is rabbeted or set back adjacent the 90 seats 15, 15, as indicated at 16, 16, in order to provide for the shifting or distortion of the metal which takes place in punching round holes through the plate, in a manner to bring the inner sides of the holes in line 95 with the vertical face of the rail-abutting shoulder; the effect of the punching at a point close to the shoulder and in such manner as to cut through the same is to force the metal outwardly from the plane of the 100 faces 16, 16, so as to form protuberances opposite the hole which project into the plane of the rail-abutting shoulder 14^a. This feature of the plate forms no part of the present invention, the same being covered in a 105 110

process described in an application filed by me on the 10th day of March, 1911, Serial No. 613,636.

19, 19 indicate elevated spike-head seats 5 on the opposite side of the rail seat of the tie-plate through which round spike holes are designed to be made and which are adapted to form bearing surfaces for the annular shoulders of the heads of the spikes 10 extending through that side of the tie-plate. It is apparent that the distance X between the shoulders 19 and the face 14^a of the rail-abutting shoulder must be constant for all of the tie-plate blanks and to roll plates 15 with this distance constant is the object of the present invention. In the process of rolling tie-plates of this kind, as at present carried on, from a continuous length of plate, the tie-plate blanks are so formed 20 that the elevated spike-head seats 19, 19 of each plate are made continuous with the elevated part or rib 14 providing the rail-abutting shoulder 14^a and the elevated spike-head seats 15, 15, of the succeeding tie-plate 25 blank, so that when the continuous plate is severed into the separate tie-plate blanks, the said elevated parts at each end of the tie-plate blank extend to the ends thereof. The difficulty with this method of rolling the tie-plate 30 is that while it is possible in thus rolling the plate, to maintain a substantially uniform distance between the rail-abutting shoulders of successive blanks, it is almost impossible to maintain in the successive tie-plate blanks of the continuous plate a uniform distance between the rail-abutting shoulder at one end and the elevated spike-head seats at the other end of the successive tie-plate blanks. As it is absolutely essential 35 that this latter-mentioned distance shall be uniform, the process heretofore carried out resulted in the formation of tie-plate blanks, many of which had to be discarded because of the lack of uniformity in the said 40 distance.

In carrying out my process I so form the face of the upper roll 11, that is to say, the face of the roll which forms the top surface of the tie-plate blanks, that the parts 30 of 50 the continuous plate between the elevated spike-head seats 19, 19 adjacent the one end of each tie-plate blank and the rib 14 providing the rail abutting shoulder 14^a and the elevated spike-head seats 15, 15 at either side

thereof adjacent the other end of the succeeding tie-plate blank are rolled to the same cross-sectional form as the main part of the tie-plate blanks. In rolling the blanks in this way, the distances separating the rail abutting shoulders 14^a of the successive 60 blanks may vary, but the distances separating the elevated spike-head seats 19 from the rail abutting shoulder 14^a of each blank is maintained constant.

The face of the roll 11 is provided with 65 recesses 20 into which the metal which forms the elevated spike-head seats 19 is adapted to be forced and with recesses 21 into which the metal, which forms the rib 14 and the elevated spike-head seats 15, is adapted to 70 be forced. Between said recesses is located a transversely extending part 22 in the face of the roll which is substantially identical in cross-section with the part 22^a which forms the main part of the tie-plate blank 75 constituting the seat for the rail.

In the case of the manufacture of the particular tie-plate blank illustrated in the drawings, the face of the roll 11 is also provided with parallel annular ribs 35 by means 80 of which the top surface of the tie-plate is provided with corrugations 36 adapted to extend transversely of the rail seat.

I claim as my invention:—

The process of rolling from a continuous 85 plate or billet a succession of integrally connected tie-plate blanks each provided adjacent one end with a transverse rib forming a rail abutting shoulder and elevated spike-head seats at either side thereof and adjacent 90 its other end with elevated spike-head seats, which consists in rolling the billet so that the tie-plates are formed end to end with their lengths extending in the direction of the length of the billet and in rolling 95 the parts of the billet intermediate said transverse rib of one tie-plate blank and the elevated spike-head seats of the proximate blank to the same cross-sectional form as the main part of the tie-plate blanks. 100

In testimony, that I, claim the foregoing as my invention I affix my signature in the presence of two witnesses, this 14th day of August A. D. 1911.

EDWIN H. BELL.
